2 Sheets-Sheet 2

UNITED STATES PATENT OFFICE

HORACE M. EATON, OF SWAMPSCOTT, MASSACHUSETTS, ASSIGNOR TO EXCEL TAPING MACHINE CO., OF LYNN, MASSACHUSETTS, A CORPORATION OF MASSACHUSETTS

TAPING MACHINE

Application filed March 7, 1930. Serial No. 484,140.

This invention relates to an improved machine for applying tape to sheet articles and more particularly to articles of this character such as the heel seam or back seam portions of shoe uppers, which comprise two sheets having marginal portions stitched together and have the body portions of the sheets disposed substantially face to face as fed to the machine. In some respects the present invention provides improvements upon the machines disclosed in the copending applications of Leland K. Butler, Serial Nos. 267,715 and 331,550, filed April 5, 1928 and January 10, 1929, respectively.

In accordance with the present invention, an improved arrangement is provided for guiding the sheet articles to pressing means such as a pair of rolls which are effective in pressing coated tape into firm adhesive engagement with the back seam portions of shoe uppers. For this purpose a yieldable member may be arranged not only to spread the body portions of each sheet away from the seam but also to cause the initial contact of the coated tape and the seamed portion of the article to which the tape is to be applied. Furthermore, the means provided herein may also aid in directing the sheet article to the pressure rolls or the equivalent and particularly is adapted to operate effectively for these purposes with a machine provided with a cutter such as is disclosed in copending application Serial No. 331,550. Preferably a spring is provided for this purpose which has a free end portion that presses the seam portion of the sheet article downwardly into engagement with a suitable surface or surfaces of a guide which receives the seam portion of the article and directs the same towards the bite of the pressure rolls and which also preferably directs the tape to the bite of the rolls. The paths of the sheet article and the tape may converge at the inner end of the guide which provided with a substantially plane surface against which the end of the spring presses the seam portion of the article, thus not only being effective in spreading the body portions of the sheet so that they tend to extend away from the seam but also causing initial adhesive

engagement of the tape and the seamed portion of the sheet article while aiding in insuring the movement of the seam in proper relation to the pressure rollers. Preferably at least one of these rollers may be provided with a suitable groove to accommodate the seam to permit the more even application of pressure to all portions of the tape particularly to margins thereof at each side of the seamed portion of the sheet article.

A machine of this character may be provided with a cutter which normally is disposed in retracted position between cutter blocks or guides thus being protected from contact with the moving tape. Preferably the guide for the tape and the sheet article is moved away from the bite of the rolls just before the cutter is advanced to engage and sever the tape. During this operation the end of the guiding and presser spring may be arranged to swing downwardly to engage the cutter block which adjoins the bite of the rolls thus cooperating with the surface of the saine in pressing the severed end of the severed tape section against the sheet article and being particularly effective in aiding the proper movement of the article to the bite of the rolls after the tape section has been freed from the restraining action of the tape guide or channel and when the sheet article is no longer in engagement with the guide.

In the accompanying drawings;

Fig. 1 is an end elevation of a portion of a tape applying machine to which my improved pressure and guiding spring have been applied;

Fig. 2 is a front elevational view of the support for the upper pressure roller of the machine, the yieldable presser and related parts;

Fig. 3 is an end elevation showing the position of the parts as the tape is being severed and while the tape and sheet article guide are both retracted;

Fig. 4 is a top view of a guide for a sheet article and tape to be applied thereto;

Fig. 5 is a section on line 5—5 of Fig. 4;

Fig. 6 is a view similar to Fig. 4 but showing an optional form of guide;

Fig. 7 is a section on line 7—7 of Fig. 6;

Fig. 8 is a view of the juxtaposed portions of the pressure rolls showing the relation of the same to a sheet article and the reinforcing tape which is being applied thereto; and

Fig. 9 is a sectional detail showing the relationship of the end of the presser spring to a seamed sheet article, reinforcing tape, and the inner end of the guide.

Referring to the accompanying drawings, the numeral 1 designates the base of a machine such as is disclosed in the above identified copending applications, numeral 2 designates an upper frame or head portion which may be movably mounted in relation to the base and may carry an upper pressure roll 3 which, during normal operation of the machine, is yieldably urged toward a lower pressure roll 4 that is mounted on the base 1.

Suitable driving means such as disclosed in the above identified copending applications may be provided to rotate the pressure rolls at substantially the same peripheral speeds.

A run of adhesively coated tape 5 may be supplied from any suitable source such as a roll 25 of this material (not shown), this run passing over an idler roll 8 and thence into engagement with a considerable peripheral portion of the lower part of the lower roll 4, thence passing over a pin or roller portion 30 of a takeup member 9 which is normally urged outward by a suitable spring (not shown) to take up the slack in the tape as it passes to the tape and sheet article guide 12, the latter being provided with a slotted portion 13 through which the tape passes to a second slot or a channel 14 (Fig. 4) at its inner end.

The guide 12 is also provided with a sheet article guiding portion 15 which is shown more particularly in Figs. 4 and 5 and comprises an upstanding ridge 16 having an outer pointed end 17, this ridge gradually decreases in height as it approaches the inner end of the guide so that its inner end forms a small rib adjoining the slot or channel 14. Preferably the surfaces of the guide adjoining the ridge 16 are flared as designated by numeral 18 to effect the spreading of the marginal portions of a sheet article A such as the back portion of a satin shoe upper. Suitable upstanding side portions 19 are provided at either side of the ridge 17 and afford flanges 20 extending inwardly in juxtaposition to the ridge 16 to cooperate therewith in guiding the seam of the sheet article A to the bite of the rolls while permitting the marginal portions adjoining the seam to be spread from the latter.

A spring-controlled catch 21 has a serrated edge portion which is adapted to engage the tape before it passes to the slot 13 of the guide and to prevent the backward movement of the tape under the action of the arm 9 or for any other reason.

A knife or cutter 25 is disposed adjoining

the guide when the latter is in normal position, then being retracted between upper and lower knife blocks 23 and 24 so that during normal operation the moving tape is protected from contact with the edge of the knife. Mechanism which operates to project the knife into engagement with the tape is first effective in moving the guide 12 away from the bite of the rolls to the position shown in Fig. 3 so that when the knife projects into engagement with the tape it severs a tape section, which is gripped between the pressure rolls, from the remainder thereof which is held by the guide 12 and prevented from possible rearward movement by the catch 21.

As shown in Fig. 8 the peripheral surface of the upper roll 3 preferably has a transverse concave curvature while the periphery of the lower roll 4 may have a transverse curvature which is in general complementary to that of the upper roll, thereby being effective in cooperating therewith in turning and shaping the sheet article as the same is being reinforced by the adhesive tape. The periphery of the lower roll may also be provided with a groove 90 to receive the seam portion of the sheet article so that pressure may be applied not only to this portion but to the adjoining parts of the body portion of the sheet to permit the adhesive application of the tape not only to the edges of the sheets which are folded over or crushed adjoining the seam but also to the body portions of the sheets which are disposed outwardly of said marginal portions.

In general it is to be understood that the foregoing description applies to a machine such as is disclosed in copending application Serial No. 331,550, the various instrumentalities for operating the cutter and for moving the guide out of the path of the same being described and disclosed in detail in said copending application which is incorporated in the present application by reference and may be regarded as forming a part of the same. A ridged guide of the general character of the guide 12 disclosed herein is also shown in copending application Serial No. 267,715.

In accordance with the present invention, the upper end of spring 30 is secured to a bracket 31 which is secured to the head 2 and which has a curved depending arm 32 having a general curvature in the direction of the curvature of the periphery of the upper pressure roll 3. The spring 30 also has a general curvature in this direction with its lower end positioned adjoining the bite of the rolls 3 and 4. Preferably as shown in Fig. 2 the sides of this spring adjoining its edge gradually merge into a somewhat rounded or bluntly pointed end portion 34. When the guide 12 is positioned as shown in Fig. 1 it provides an end portion 41 disposed in

wardly of the tape channel 14 and the spring 30 is so flexed that it presses downwardly upon the sheet article and the tape which is passing over the end portion 41 of the guide 5 (Fig. 9). Thus the presser spring 34 is effective in causing the body portions of the sheets to spread away from the seam portion of the sheet article A and in pressing the seam portion thereof into initial contact with the coated face of tape 5.

Furthermore, the somewhat pointed end of the spring tends to hold the seam portion of the sheet article properly centered as it passes from the ridge 16 to the bite of the rolls. In other words the spring 34 directs the sheet article to the bite of the rolls while initially engaging the tape therewith, as well as spreading the body portions of the sheet and applying initial pressure to the seam portion. Accordingly this member aids in insuring the smooth and uniform application of the adhesively coated tape to the seam portion of the sheet article.

As the rear edge of the sheet article approaches the bite of the rolls, the operator will cause the guide 12 to swing downwardly to the position shown in Fig. 3 and whereupon the cutter 25 is automatically projected to sever the tape, thus the severed tape section 30 may have a length which preferably may be slightly less than the length of the seam which is being reinforced. Under these conditions, the resiliency of the spring 30 causes its end to press the sheet article and the end 35 of the tape section downwardly against the upper cutter block 23 thus cooperating with the latter in imparting a suitable drag upon the end of the severed tape section and insuring the proper initial contact of the same with 40 the seam before it is pressed in firm adhesive engagement therewith. Under these conditions, when the article and tape section have moved out of engagement with the guide 12, the spring 30 is particularly advantageous in 45 ensuring proper engagement of the tape with the seam portion of the sheet article and in properly directing the article and tape to the pressure rolls. When the cutter is retracted the guide 12 may return to its normal operating position being effective in inserting the severed end of the tape run between the rollers and also in flexing the spring 30 so that its end portion resumes the position shown in Fig. 1, thus being ready again 55 to impart pressure to the seam of a succeeding sheet article.

When leather back seamed portions are to be reinforced with an adhesively coated tape, a guide such as shown in Figs. 6 and 7 may 60 be provided having a block portion 60 with a groove 61 to receive the seamed portion of the upper member and having a tape channel 62 adjoining the inner end of the guide, the extreme end of the latter designated by 65 numeral 41^a being positioned in the same gen-

eral manner as the inner end 41 of the guide 12 and cooperating with the guiding and presser spring 30 in the same general manner. Accordingly it is evident that the principles of this invention may be employed with 70 a sheet article formed of satin or similar fabric and having appreciable marginal portions adjoining the seam which must be folded back before the reinforcing tape is applied thereto or that it may be employed for the 75 reinforcement of leather articles which have narrow marginal portions which need merely to be crushed or pressed downwardly as the reinforced tape is applied thereto.

From the foregoing it is evident that I 80 have provided means which permit the initial adhesive engagement of coated tape with a seamed sheet article before these elements pass between the main pressure applying elements such as pressure rolls and that this 85 means may also be effective in spreading the body portion of the sheets away from the seam while imparting an initial pressure to the seamed portion, i. e. the margins of the sheet directly adjoining the seam. At the same 90 time this arrangement insures the proper application of a severed end of a tape section to the last portion of a seamed article which passes to the pressure applying rolls.

I claim:

1. In a machine of the class described, a pair of juxtaposed rolls, means for supplying adhesive tape between the rolls, and guide means adjoining the rolls for sheets which are stitched substantially face to face, said 100 guide means including a part yieldably to engage the body portions of the sheets adjoining the seam, and a member providing a surface against which the seam is pressed by said member, whereby the sheets are spread 105 away from the seam and the article is directed between the rolls and into adhesive engagement with the tape.

2. In a machine of the class described, a pair of rolls, a guide for a sheet article comprising sheets stitched substantially face to face, said guide having a portion to engage the seam of said article and another portion forming a tape guide, a spreading and guiding member juxtaposed to said guide and arranged yieldably to press the sheets adjoining the seam toward a portion of the guide which is juxtaposed to the rolls, thereby 115 spreading the sheets from the seam.

3. In a machine of the class described, a 120 pair of rolls, a guide for a sheet article comprising sheets stitched substantially face to face, said guide having a portion to engage the seam of said article and another portion forming a tape channel, a spreading and guiding member juxtaposed to said guide and arranged yieldably to press the sheets adjoining the seam toward a portion of the guide which is juxtaposed to the rolls, thereby 125 spreading the sheets from the seam, said 130

- tape channel being arranged to supply the tape into adhesive engagement with the seam as it passes between the guide and said member, whereby the tape is initially applied to the seam before passing between the rolls.
4. In a machine of the class described, a pair of rolls, one of said rolls having a peripheral groove, a guide for a sheet article comprising sheets stitched substantially face to face, said guide having a portion to engage the seam of said article and another portion forming a tape guide, a spreading and guiding member juxtaposed to said guide and arranged yieldably to press the sheets adjoining the seam toward a portion of the guide which is juxtaposed to the rolls, thereby spreading the sheets from the seam and thus properly directing the seam to the peripheral groove of the roll.
5. In a machine of the class described, a pair of rolls, a guide for a sheet article comprising sheets stitched substantially face to face, said guide having a portion to engage the seam of said article and another portion forming a tape guide, the end of said guide adjoining the bite of the rolls being arranged so that the tape and sheet article pass into contact, and a spreading and guiding member arranged yieldably to press the sheet article and tape toward said end of the guide thereby spreading the body portions of the sheets from the seam and initially pressing the same into engagement with the tape before passing between the rolls.
6. In a machine of the class described, a pair of rolls, a guide for a sheet article comprising sheets stitched substantially face to face, said guide having an upstanding ridge to engage marginal portions of the sheets adjoining the seam and to spread the same therefrom, the guide having a tape channel to supply tape in adhesive engagement with the spread marginal portions at the inner end of the guide, the end of said guide adjoining the bite of the rolls being arranged so that the tape and sheet article pass into contact, and a spreading and guiding member arranged yieldably to press the sheet article and tape toward said end of the guide thereby spreading the body portions of the sheets from the seam and initially pressing the same into engagement with the tape before passing between the rolls.
7. In a machine of the class described, a pair of rolls, a guide for a sheet article comprising sheets stitched substantially face to face, said guide having a portion to engage the seam of said article and another portion forming a tape guide, a spring having an end portion with a curvature in the same general direction as that of the periphery of one of the rolls and having its end juxtaposed to the guide member and arranged yieldably to press the sheets adjoining the seam against

said guide and to spread the body portions of the sheets from the seam.

8. In a machine of the class described, a pair of rolls, a guide for a sheet article comprising sheets stitched substantially face to face, said guide having a portion to engage the seam of said article and another portion forming a tape guide, a spring having an end portion with a curvature in the same general direction as that of the periphery of one of the rolls and having its end juxtaposed to the guide member and arranged yieldably to press the sheets adjoining the seam against said guide and to spread the body portions of the sheets from the seam, said tape guide portion being arranged to supply the tape in adhesive engagement with the seam as it passes between the guide and said spring, whereby the tape is initially applied to the seam before they pass between the rolls.

9. In a machine of the class described, a pair of rolls, one of said rolls having a peripheral groove, a guide for a sheet article comprising sheets stitched substantially face to face, said guide having a portion to engage the seam of said article and another portion forming a tape guide, a spring having an end portion with a curvature in the same general direction as that of the periphery of one of the rolls and having its end juxtaposed to the guide member and arranged yieldably to press the sheets adjoining the seam against said guide and to spread the body portions of the sheets from the seam, and thus properly to direct the seam to the peripheral groove of the roll.

10. A machine for acting upon a sheet article comprising two sheets which are stitched together, said machine comprising a portion for applying pressure to the seam, a guide to direct adhesive tape into engagement with the seam as it passes to said means and to direct the seamed portion of the article to said means, and a presser member yieldably urged toward said guide to cooperate therewith in spreading the body portions of the sheets away from the seam and in yieldably pressing the seam against the tape, as the article and tape pass to said pressure applying means, said guide being movable out of juxtaposition to the presser member, and a part positioned to cooperate with the presser member in initially pressing the tape and seam when the guide is thus moved.

11. In a machine of the class described, a pair of juxtaposed rolls, means for supplying adhesive tape between the rolls, and guide means adjoining the rolls for sheets which are stitched substantially face to face, said guide means including a presser yieldably to engage the body portions of the sheets adjoining the seam, a member providing a surface to cooperate with the presser in pressing the seam, whereby the sheets are spread away from the seam and the article is directed be-

tween the rolls and into adhesive engagement with the tape, a cutter movable to a position to sever tape passing to the rolls, said member being movable away from the presser when the cutter is actuated, and another part providing a surface similarly to cooperate with the presser when the first member is moved away.

12. In a machine of the class described, a pair of rolls, a guide for a sheet article comprising sheets stitched substantially face to face, said guide having a portion to engage the seam of said article and another portion forming a tape guide, a spring having an end portion juxtaposed to the guide member and arranged to cooperate therewith yieldably to press the sheets adjoining the seam and to spread the body portions of the sheets from the seam, and a cutter movable from a retracted position to a cutting position, a block adjoining said cutter, said guide being movable away from the spring when the cutter is moved from retracted position, the spring end being arranged to cooperate with the block in initially pressing the article when the guide is moved away from the spring.

13. In a machine of the class described, a pair of rolls, a guide for a sheet article comprising sheets stitched substantially face to face, said guide having a portion to engage the seam of said article and another portion forming a tape guide, a spring having an end portion juxtaposed to the guide member and arranged to cooperate therewith yieldably to press the sheets adjoining the seam and to spread the body portions of the sheets from the seam, and a cutter movable from a retracted position to a cutting position, a block adjoining said cutter, said guide being movable away from the spring when the cutter is moved from retracted position, the spring end being arranged to cooperate with the block in initially pressing the article when the guide is moved away from the spring, the spring resuming its normal cooperative relationship to the guide when the latter is returned into juxtaposition thereto.

14. A machine to apply reinforcing tape to the seam portion of a sheet article that comprises two sheets which are stitched together, said machine comprising means for applying pressure to the seam, a guide to direct adhesive tape into engagement with the seam as it passes to said means and to direct the seam portion of the article to said means, said guide having a ridge, the end of the guide providing a substantially flat surface adjoining the end of the ridge and adjoining said means, and a member yieldably urged toward the end of the guide to cooperate with the substantially flat surface of the ridge to cooperate with said surface in flattening the body portions of the sheets away from the seam and in yieldably pressing the seam against the tape prior to the

passage of the tape and seam to said pressure applying means.

Signed by me at Boston, Massachusetts this 28th day of February 1930.
